(57) **CLAIM**

The ornamental design for a rotational valve assembly, as shown and described.

DESCRIPTION

FIG. 1 is a perspective view of a rotational valve assembly according to the present invention;
FIG. 2 is a side view of the rotational valve assembly of FIG. 1;

FIG. 3 is a front view of the rotational valve assembly of FIG. 1; and,

FIG. 4 is a back view of the rotational valve assembly of FIG. 1.
